UNITED STATES PATENT OFFICE.

ALONZO LINTON BAUSMAN, OF CHICOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

CANDY-MAKING APPARATUS.

Application filed December 2, 1920. Serial No. 427,781.

To all whom it may concern:

Be it known that I, ALONZO LINTON BAUSMAN, citizen of the United States, residing at Chicopee, in the county of Hampden and State of Massachusetts, have invented new and useful Improvements in Candy-Making Apparatus, of which the following is a specification.

This invention relates to an apparatus which is particularly designed for use in candy making to facilitate the packing of the coated confections and cool them prior to packing. An example of an apparatus of this class is shown in U. S. Letters Patent #1,123,934 granted January 5, 1915, to Schrafft, Blake and Lorentzen.

An object of the invention is to improve apparatus of the general type shown in said patent by the utilization of space formerly wasted, thereby rendering the apparatus less bulky.

Another object of the invention is to provide an apparatus of the type described, wherein the candy trays are carried in a substantially rectangular path and eventually along a packing table, characterized in that the trays are carried along the latter by the upper of the rectangular system of conveyors, whereby the apparatus may largely be located below the packing table and thus greatly reduced in height over that shown in the above-mentioned patent.

Another object of the invention is to utilize the space within the borders of the rectangularly arranged conveyors, by providing other conveyors therein, thus lengthening the path of travel of the trays with relation to the cubic space occupied by the apparatus.

Another object of the invention is to provide an improved arrangement of the cooling means in an apparatus of the class described.

Another object of the invention is to provide in an apparatus of the type defined, tray conveying means operable step by step and housed within a suitable enclosure, together with cooling means including directing devices to direct the cooling medium between the trays when at rest.

Other objects and advantages will appear

in the following description and in the illustrative embodiment of the invention in the accompanying drawings, in which—

Figs. 1^a and 1^b are elevational views each showing half the apparatus. These views should be imagined to be joined together along the line *a*—*b* to produce a complete elevational view of the apparatus. In both these figures the closure members which encase the major portion of the apparatus have been largely broken away in order to reveal the interior mechanism;

Fig. 2 is a conventional plan view of the driving mechanism shown in Fig. 1^a;

Fig. 3 is an elevational view of a portion of the driving mechanism, showing the means for intermittently operating certain conveyers while others are at rest and vice versa;

Fig. 4 is a diagrammatical view illustrating the circuitous path along which trays may be carried by the several conveyers;

Fig. 5 is a cross-sectional view taken on the line *a*—*b* of Fig. 1^b; and

Fig. 6 is a fragmentary elevational view partly in section, showing the means for introducing a temperature controlling medium into the casings which house the tray conveyers.

The apparatus, in general, comprises a plurality of conveyers, some of which travel vertically and others horizontally, and all of which are so arranged that a tray placed in one will be automatically transferred to the next, and so on, so that the tray is eventually carried back to its starting point after having travelled in a comparatively long circuitous path. Thus, as diagrammatically shown in Fig. 4, the trays *t* are first carried downwardly by one conveyor, then horizontally into a second vertical conveyor, thence upwardly and then horizontally into a third vertical conveyor, thence downwardly and then horizontally into a fourth conveyor which carries the trays upwardly until they can be removed by a horizontal conveyor, which returns them to the first vertical conveyor.

The apparatus is intended to accomplish similar results to those accomplished by the apparatus shown in the above-mentioned

patent and is characterized by improvements designed to render the apparatus more compact than that of said patent. Instead of merely carrying the trays in a rectangular path, they are also caused to move back and forth within the borders of the rectangular path by conveyers which are located intermediate the end conveyers. As many intermediate conveyers may be provided, as desired, although the number of intermediate conveyers should be multiples of two. The two intermediate conveyers shown will amply suffice to illustrate the principle involved.

15 Referring to Figs. 1^a and 1^b, the end vertical conveyers are represented generally by V and V' and the intermediate vertical conveyers by v and v'. The horizontal conveyers are shown at H and H', the conveyer H' including a section h' which is made separate for reasons hereinafter to be explained. A third horizontal conveyer h serves to transfer trays from conveyer v to conveyer v'.

25 All the vertical conveyers are of like construction and a detailed description of one, as conveyer v, will suffice for all. The conveyer v (Fig. 5) consists of two spaced pairs of endless chains 10 and 10', the inner and 30 adjacent laps of which travel in parallel paths. A series of angles 11 connect the two chains 10 together at suitably spaced intervals and like angles 11' connect the chains 10'. The angles 11 and 11' are so 35 mounted on their respective chains that each angle 11 lies opposite, and in the same horizontal plane with an angle 11'. The chains 10 are supported by suitable sprockets from upper and lower shafts 12 and 13, the upper 40 being an idler shaft and the lower a driven shaft. The chains 10' are similarly supported by similar shafts 12' and 13'. The shafts 13 and 13' are driven, by means to be described simultaneously, at the same speed 45 and in opposite directions and so that the inner lap of the chains 10 and 10' ascend. A tray t is moved horizontally, as will appear, between the chains 10 and 10' while the latter are at rest and is left with one 50 edge resting on an angle 11 and the opposite edge on the corresponding angle 11'.

The conveyer V is of exactly similar construction and one section is driven by a shaft 14, which aligns with the described 55 shaft 13, the other section being driven by a similar shaft on the opposite side of the machine which shaft aligns with the shaft 13'. The shafts 13 and 14 extend along the frame A of the machine into close proximity 60 (Fig. 1^a) and each is provided with a bevel gear 15. Both these gears are driven by a common bevel gear 16, whereby shaft 14 rotates in a direction opposite to shaft 13. It is to be understood that similar bevel 65 gears are provided on the opposite side of

the machine for a like purpose. In fact, all the driving mechanism shown on the front side of the machine in Figs. 1^a and 1^b is duplicated on the back side and need not therefore be described in detail. Such parts 70 of the driving mechanism on the rear side of the machine as are shown have been given in the same reference numerals as the corresponding parts on the front of the machine except that such numerals are primed. Gear 75 16 is fixed to a vertical shaft 17 which carries a bevel gear 18 and the latter meshes with a bevel gear 19, fixed to one end of a cross shaft 20 mounted in frame A. Shaft 20 carries a gear 19' at its opposite end which 80 drives a vertical shaft 17' through a bevel gear 18'. It is to be noted that shafts 17 and 17' are driven in opposite directions, whereby shaft 13 turns in a direction opposite to that of shaft 13' and shaft 14 in a 85 direction opposite to that of its corresponding shaft (not shown).

The chains 21 for conveyer v' are carried by upper and lower sprockets 22 and 23 respectively, the sprockets 23 being free 90 to turn on the drive shaft 13 while sprockets 22 are fixed to a shaft 24. The latter is driven from shaft 13 by a vertical shaft 25, which is supported at its ends by brackets 26 and 27 from shafts 13 and 24, respectively 95 and is connected to shafts 13 and 24 by the bevel gears shown. This arrangement causes the conveyer v' to travel downwardly while conveyer v travels upwardly.

Conveyer V' is driven directly from 100 shafts 13 and 13' in a manner exactly like conveyer v. All the vertical conveyers are therefore driven from the one shaft 20 heretofore described.

The horizontal conveyers are likewise 105 driven from a single hollow shaft 28 mounted on a shaft 29 parallel to shaft 20. The conveyer H' consists of a single chain, having lugs 30, said chain being carried by suitable sprockets 31 on cross shafts 32 and 110 33. Shaft 32 is directly driven from shaft 28 by means of a chain 34 which is driven by a sprocket 35 thereon. The conveyer h' also consists of a single chain which carries lugs 37 and is supported by suitable sprockets from two cross shafts 38 and 39. Shaft 39 is driven from shaft 33 by the spur gears 40. The conveyor H likewise consists of a single chain which carries lugs 42 and travels around suitable sprockets on two spaced 115 shafts 43 and 44 and the latter is driven from shaft 38 by a chain 45. Intermediate cross shafts 46', each with a sprocket, are provided between the end shafts 43 and 44. The conveyer h consists of a single chain having lugs 45', said chain being carried by sprockets on shafts 46 and 47, which are arranged parallel, but below, and in a different vertical plane than the conveyer H'. Shaft 46 carries a sprocket 48 which is 120 125 130

driven by a chain 49 from a sprocket 50 on shaft 28. Thus, all the horizontal conveyers move simultaneously and the connecting gearing between conveyers H' and h' , and 5 between conveyers h' and H , are such that all three conveyers move at substantially the same speed. Conveyers H and h' likewise travel in the same direction, which is opposite from the direction of travel of conveyers 10 H' and h , by reason of the gears 40.

The driving mechanism for the conveyers will now be described with reference to Figs. 1^a, 2 and 3. The shaft 20, heretofore described as driving all the vertical conveyers, 15 is driven by spur gears 51 from a shaft 52. The latter has fixed thereto a gear 53 and a like gear 54 is fixed to the shaft 28, which drives all the horizontal conveyers. Between shafts 47 and 49 is a shaft 55, which 20 has fixed thereto an intermittent gear 56. The latter, during one-half of its rotation, drives gear 52 and, during the other half, drives gear 53 while gear 52 remains stationary. Thus, all the horizontal conveyers 25 move simultaneously while the vertical conveyers are at rest and vice versa. Shaft 55 may be driven in any suitable manner but, preferably, at relatively low speeds. To this end, speed reduction gearing is provided to 30 connect shaft 55 to the source of power, which, for example, may be an electric motor M. Shaft 55 has fixed thereto a gear 57, which meshes with a gear 58, fixed on a shaft 59. Also fixed on shaft 59 is a gear 60, 35 which drives a gear 61, loosely mounted on shaft 55. Fixed to gear 61 is a gear 62, which drives a gear 63, fixed on shaft 29. Shaft 29 carries a pulley 64, which is driven by a belt 65 from a pulley 66 on a jack shaft 67, and the latter is driven by a belt 68 from 40 motor M. The driving connections described are such as to afford a substantial speed reduction between motor M and shaft 55.

45 All the shafts, heretofore described, are suitably mounted in a frame A, which, as indicated, consists of a series of uprights suitably tied together by horizontal longitudinal and transverse members, the whole 50 affording an openwork frame to receive the several conveyers described. This frame is, preferably, higher at each end than in the middle and, between the ends, supports two packing tables T, one on each side of the 55 horizontal conveyer H' . These tables consist merely of shelves (Fig. 5) placed at a convenient height for the packers, who are located alongside the shelves and select candies from the trays t as they pass on conveyer H' and pack them in suitable boxes. The conveyer H' is arranged in a plane 60 parallel to but slightly above the tables T and upright boards 69, one on each side of conveyer H' , extend upwardly from the 65 shelves with their upper edges substantially

flush with the top of the trays t which pass closely therebetween. These boards 69 form side guides for the trays t .

Runways 70 suitably supported from boards 69 (Fig. 5) are provided, one on 70 each side of conveyer H' to support trays t and the upper lap of conveyer H' travels in a central, channel-shaped guide 71, which keeps the chain from sagging. The runways 70 extend from conveyer V to conveyer V'. Similar runways 73 (Fig. 5) are provided, to support the trays t as they travel from conveyer V to conveyer v, together with side guides 74.

The conveyer V is completely housed in 80 except for an opening σ (Fig. 1^a) by plates, such as the end and side plates 75 and 76, shown in Fig. 1^a. One of the end plates 76 is provided with a vertical series of horizontally disposed louvers 77 (Fig. 6) and these 85 louvers are encompassed by a housing 78, to which the temperature controlling medium, such for example as cooling air, is admitted by a pipe 79, to which it is suitably supplied, as by a blower B (Fig. 1^a), driven by a belt 90 from motor M.

The conveyers v, v' and V' are likewise located in an enclosure formed by side plates 95 81 and end plates 82. One end plate 82 is provided with a housing 83, similar to the housing 78, to which the temperature controlling medium is supplied by a pipe 84 from blower B. Louvers (not shown) are provided in this end plate 82 in a manner similar to that shown in connection with plate 75. These louvers and the louvers 77 serve to effectively distribute the cooling medium in the conveyer enclosures and are preferably so arranged as to direct the incoming medium between the trays t , when 100 the latter are at rest, as clearly shown in Fig. 6.

Suitably supported above the packing 110 tables are shelves S, upon which the packed boxes of confections may be placed. Mounted between these shelves S, and between side guide plates 85, is a conveyer C, consisting of a belt mounted on and extending between pulleys 86 and 87. Conveyer C, in its upper lap of travel, is held against sagging by a support 88. The conveyer C is intended to travel in the direction of the arrow and its delivery end is preferably adjustable so that the packed boxes may be delivered at various levels, as desired. For example, the boxes 115 may be delivered to a table or to a conveyer mounted thereabove. To this end the conveyer is deflected downwardly by a roll 89 and passes to and around a roll 90 and thence upwardly over a roll 91. The delivery end of the conveyer C is mounted in a frame, consisting of a support 92 for the upper lap of travel of the conveyer and side guides 93. The described roll 87 is mounted 120 in this frame and the latter is pivoted about 125 95

the axis of roll 91. Arms 94, capable of being secured at their lower ends in various positions of adjustment to frame A, support the delivery end of the conveyer and permit it to be adjusted to various levels as desired. The conveyer C is driven by a chain 96 from a sprocket 97, fixed on the described shaft 59 which turns continuously, and chain 96 extends over suitable idlers 98 to a sprocket on roll 90.

Preferably, in order to provide for convenient access to the interior of the machine, the various housing plates described are mounted for convenient removal, as clearly shown in Fig. 1^b in connection with the plate 81. Preferably also, at least one section of each vertical conveyer is mounted so as to be readily movable to allow access to the trays to permit their removal, whenever necessary or desired, or for other purposes.

This latter feature is illustrated in Fig. 5 in connection with one section of conveyer v and, as there shown, the upper and idler shaft 12' is mounted in a frame F, which is fulcrumed on the lower and driving shaft 13'. The frame F may be releasably held in its normal position by any suitable means, such as a latch arm 99 pivoted to frame A and depending therefrom with its lower end forked to fit over shaft 12' and prevent it from displacement in either direction. By swinging arm 99 upwardly on its pivot 100, the forked end is disengaged from shaft 12' and the latter and frame F can be swung outwardly to allow access to the interior of the machine.

In operation, an attendant is stationed adjacent the conveyer V, which by preference is located adjacent the delivery end of a candy coating machine, as exemplified in the patent above referred to, and this attendant loads empty trays t with the coated confections. This loading is generally accomplished by removing an empty tray t, placing it alongside the delivery belt of the coating machine, and sliding the plaques (waxed papers on which the coated candies are delivered) from said belt into the tray. The loaded tray is then placed in conveyer V near the upper end thereof and travels slowly downward step-by-step, finally coming to rest in alignment with the lower runways 64.

As the tray thus comes to rest, conveyer H is set in motion and a lug 42 thereon engages this tray and moves it one step toward conveyer v. This step is slightly greater than the length of tray t. A second similar step of movement of conveyer H carries tray t forwardly to a position beneath the driving mechanism and a third step carries tray t into the conveyer v, while it is at rest with two of its angles 11 and 11' aligned with the runways 74. The tray then travels slowly upwardly in conveyer v

and, while it moves one step upwardly, that lug 42, which moved it into conveyer v, travels to a position adjacent conveyer v', so that in a succeeding step of movement it removes a tray from conveyer v' into conveyer V'. All the vertical conveyers come to rest with their angle pieces in alignment.

The transfer of trays from the upper part of conveyer v to the conveyer v' is effected by the lugs 45' on the conveyer h during its lower lap of travel.

The tray t is carried upwardly step-by-step in conveyer V' and eventually comes to rest in alignment with the upper runways 70 and below the conveyer h'. At this time, a lug 37 of conveyer h' moves to the left (as viewed in Fig. 1^b) during the lower lap of travel of the conveyer and moves the tray out of conveyer V' and upon the runways. The tray is left on the runways in position to be engaged by a lug 30 of conveyer H' on a succeeding step of movement. The conveyer H' carries the tray step-by-step to the left, finally leaving it upon the runways about a tray's length to the right of the conveyer V, in such position that when later moved by abutment with a succeeding tray, it will be carried, correctly positioned, into conveyer V. Empty trays deposited in the latter are withdrawn, either partially or entirely, through opening o for the purpose of filling them with freshly coated candies.

Thus, I have provided an apparatus through which freshly coated candies, or other articles, may be carried and cooled, or otherwise subjected to a temperature changing medium, and then conveyed along packing tables in position for the packers to conveniently select and remove them for packing.

The apparatus is particularly characterized by its compactness and low height, the uppermost conveyer serving to distribute the candies to the packers and being only slightly higher than the packing table. The provision of means, whereby the cooling medium is evenly distributed in a systematic manner in the several enclosures for the conveyers, is also important inasmuch as it permits effective cooling.

In this connection, the cool air blown into the machine finally escapes into the room in which the apparatus is located. Candy coating machines are usually arranged to deliver the coated candies into so-called cold rooms and, instead of employing separate cooling means therefor, the cold air may be first supplied to, and utilized in, the described apparatus and having cooled the candies, allowed to escape from the apparatus to reduce the temperature of the room.

The invention has been disclosed herein in an embodiment at present preferred, for the purposes of illustration, but the scope

of the invention is defined by the appended claims rather than by the foregoing description.

What I claim is—

first named horizontally movable conveying means to carry a tray from the opposite end of the first named intermediate conveyer into the corresponding end of the adjacent intermediate conveyer.

8. In apparatus of the class described, a frame, two endless conveyers mounted in spaced parallel relation, and means provided at spaced intervals on said conveyers

to support the ends of trays disposed between the adjacent laps of said conveyers, one of said conveyers being mounted in said frame for movement bodily away from the other conveyer to permit access to the space therebetween.

In testimony whereof I have affixed my signature.

ALONZO LINTON BAUSMAN.
